(57) CLAIM

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; FIG. 7 is a rear view of the garment of FIG. 1 with the vent on the back of the garment shown in a closed position; FIG. 8 is a rear perspective view thereof; FIG. 9 is a front view of the garment of FIG. 1 shown in an environment of use; and, FIG. 10 is a rear view of the garment of FIG. 1 shown in an environment of use.

The portions of the garment shown in dash-dash broken lines in FIGS. 1-10 do not form part of the claimed design. The dash-dash broken line showing of the hands, legs, torso, and head in FIGS. 9-10 is for the purpose of illustrating portions of the environmental structure and forms no part of the claimed design. The dotted broken lines shown in FIGS. 1-10 illustrate stitching and do not form part of the claimed design.

1 Claim, 10 Drawing Sheets
